No. 825,136.

PATENTED JULY 3, 1906.

T. KURRELL,
DISPENSING DEVICE.
APPLICATION FILED JULY 3, 1905.

UNITED STATES PATENT OFFICE.

THEODOR KURRELL, OF ST. LOUIS, MISSOURI.

DISPENSING DEVICE.

No. 825,136.

Specification of Letters Patent.

Patented July 3, 1906.

Application filed July 3, 1905. Serial No. 268,182.

To all whom it may concern:

Be it known that I, THEODOR KURRELL, a citizen of the United States, residing at St. Louis, State of Missouri, have invented certain new and useful Improvements in Dispensing Devices, of which the following is a full, clear, and exact description, reference being had to the accompanying drawings, forming a part hereof.

10 My invention has relation to improvements in dispensing devices for semiliquid or plastic substances, such as mustard, salves, pomades, soaps, vaseline, sauces, and the like; and it consists in the novel construction and arrangement of parts more fully set forth in the specification, and pointed out in the claims.

In the drawings, Figure 1 is an elevation of the device with wall partly broken away. Fig. 2 is a middle vertical section on line 2 2 of Fig. 5. Fig. 3 is a top plan view. Fig. 4 is a horizontal section on line 4 4 of Fig. 2. Fig. 5 is a horizontal section on line 5 5 of Fig. 2, showing the parts in normal position. Fig. 6 is a similar section showing the actuating cam-disk turned to a position to open the slide valve or gate, and Fig. 7 is a vertical section on line 7 7 of Fig. 5.

The present device, though specially designed for dispensing mustard at the dinner-table, may be used for dispensing predetermined quantities of any plastic or semisolid substances on the order above specified. Its object is to retain the mustard in a receptacle from which the air is excluded, so that it

35 may remain permanently fresh.

A further object is to dispense with the use of spoons and with the necessity of serving the same from a spoon.

40 A further object is to prevent smearing the mustard unnecessarily over surfaces where it is not desirable and, in fine, to provide a receptacle from which the material may be dispensed with cleanliness and in definite quantities.

45 In detail the invention may be described as follows:

Referring to the drawings, 1 represents a suitable holder or receptacle provided with a cover or screw-top 2, which serves as a support for the upper end or spindle 3 of the central operating-screw 4, the lower spindle 5 of the screw passing loosely through a central opening of the bottom of the receptacle and terminating in a reduced end or extension 5', which rests in a socket in the bottom of the removable screw base or bottom 6. Be-

tween the bottom of the receptacle and the base 6 is a chamber 7 for the housing of a portion of the operating parts of the device, a suitable discharge-tube 8 leading from the receptacle-bottom to a discharge-opening 9 of the screw-base. Passed over the spindle 5, which is flattened on one side, is the hub portion of a cam-disk 10, the flattening referred to preventing rotation of the cam about the spindle. The cam-disk is provided with a V-shaped recess 11, to the base of which is normally forced and held a pin 12 by the resilient action of the terminal arm of a spring 13, whose fixed end is secured to a post 14 on the screw-base 6. The pin 12 is secured to a sliding gate or valve 15, which controls the discharge end of the tube 8, the gate having formed therein an elongated slot 16 for the passage therethrough of the spindle 5 and to allow for the necessary reciprocations of the gate, as will more fully hereinafter appear. The gate has an upturned wall or end 15', against which the spring-arm 13 bears, tending to always force the gate to its closed position—that is, over the discharge end of the tube 8. The gate is guided within grooves or ways formed or channeled out from the floor of the base 6, Fig. 7. Adapted to travel along the screw 4 is a follower or piston 16, capable only of longitudinal motion on the screw, but not capable of rotation about its axis. The upper spindle of the screw is provided with a milled head 17, below which is secured an arm 18, coöperating with an index-mark 19, from which as a starting-point the arm marks a complete revolution for a single rotation of the screw and for an advance of the piston 16, corresponding to a single discharge of the material forced through the opening 9.

The operation of the device is as follows: By removing the screw top or cover 2 the screw 4, with its follower 16, may be withdrawn and the receptacle filled with the material M to be dispensed. The parts are then replaced and the screw-top secured in place. Normally the gate 15 is closed over the discharge-opening 9, being held in said closed position by the spring 13, the pin 12 on the gate for the closed position of the latter occupying a position at the base of the recess 11, Fig. 5. By turning the milled head 17 in the direction shown by the arrows in Figs. 3 and 6 the pin 12 rides along the cam edge of the disk 10, the eccentric formation of such edge forcing the pin 12 and gate 15

outwardly, thus uncovering the opening 9 at the bottom of the tube 8, Fig. 6. At the same time the follower or piston 16 is descending along the screw 4, and in its descent 5 it forces or expels the contents of the receptacle through the tube 8 and discharge-opening 9. The discharge of the material will continue as long as the screw 4 is turned and as long as the opening 9 is uncovered. By 10 the time the screw makes a complete revolution (by which time the arm 18, which initially started from the mark 19, will again come opposite said mark) the resiliency of the spring 13 will suddenly force the gate to 15 its closed position, driving the pin 12 to the base of the recess 11 along the radial edge of said recess. The parts are thus brought back into their original position, when a second turn of the screw will force another portion 20 of the contents through the opening 9. This can be repeated until the follower or piston 16 has been driven to the bottom of the receptacle, by which time it will have forced out the entire contents thereof.

25 Obviously I may depart in minor details of construction without affecting either the nature or spirit of my invention.

Having described my invention, what I claim is—

- 30 1. In a dispensing device of the class described, a suitable receptacle, a follower therein, means for actuating the follower, a valve-controlled discharge-opening leading from the receptacle, and means for uncovering said opening upon movement of the follower against the contents of the receptacle, whereby said contents may be expelled by said follower, substantially as set forth.
2. In a dispensing device of the class de-40 scribed, a suitable receptacle, a follower movable against the contents thereof, means for actuating the follower, a discharge-opening leading from the receptacle, a gate normally closing said opening, and means for shifting said gate and uncovering the opening with the expelling movement of the follower, substantially as set forth.
- 45 3. A dispensing device of the class de-

scribed comprising a receptacle, a screw passing centrally through the same, a piston or follower on the screw, a chamber at the base of the receptacle, a spindle forming the lower extension of the screw and entering said chamber, a cam-disk mounted on the spindle, said disk having a peripheral recess, a sliding gate mounted at the base of the chamber and controlling a discharge-opening from the receptacle, a spring bearing against the gate and normally forcing the same to a closed position, a pin on the gate normally resting at the base of the recess and adapted to travel along the cam edge of the disk, an elongated slot formed in the gate for the passage of the screw-spindle, and a discharge-tube leading from the receptacle to the discharge-opening aforesaid, the parts operating substantially as, and for the purpose set forth.

4. In a dispensing device of the class described, a suitable receptacle, a screw passing centrally through the same, a piston or follower on the screw, a discharge-opening leading from the bottom of the receptacle, a spring-controlled gate normally closing said opening, and intermediate connections between the screw and gate for shifting the gate to open position upon a turning of the screw for the expelling movement of the follower, substantially as set forth.

5. In a dispensing device of the class described, a suitable receptacle, a screw passing through the same, a piston or follower on the screw, a discharge-opening leading from the bottom of the receptacle, a spring-controlled reciprocating gate normally closing said opening, and intermediate connections between the screw and gate for shifting the gate to open position upon a turning of the screw for the expelling movement of the follower, substantially as set forth.

In testimony whereof I affix my signature in presence of two witnesses.

THEODOR KURRELL.
